(57) CLAIM

The ornamental design for an oral dental appliance, as shown and described.

DESCRIPTION

FIG. 1 is a top, front, left side perspective view of an oral dental appliance showing my new design;

FIG. 2 is a front elevation thereof;

FIG. 3 is a rear elevation thereof;

FIG. 4 is a right side elevation thereof with the left side being a mirror image;

FIG. 5 is a top plan view thereof; and,

FIG. 6 is a bottom plan view thereof.

The broken line portion of the figure drawings is included to show unclaimed subject matter only and forms no part of the claimed design.
